(57) **CLAIM**

The ornamental design for an ultra-small, micro-volume instrument unit assembly, as shown and described.

DESCRIPTION

FIG. 1 is a top, front, right isometric perspective view of an ultra-small, micro-volume instrument unit assembly having a design in accordance with an embodiment of the present invention;

FIG. 2 is a front elevation view of the ultra-small, micro-volume instrument unit assembly of FIG. 1;

FIG. 3 is a left elevation view of the ultra-small, micro-volume unit instrument assembly of FIG. 1;

FIG. 4 is a right elevation view of the ultra-small, micro-volume instrument unit assembly of FIG. 1;

FIG. 5 is a rear elevation view of the ultra-small, micro-volume instrument unit assembly of FIG. 1;

FIG. 6 is a top plan view of the ultra-small, micro-volume instrument unit assembly of FIG. 1;

FIG. 7 is a bottom plan view of the ultra-small, micro-volume instrument unit assembly of FIG. 1;

FIG. 8 is an exploded top, front and right perspective view of the ultra-small, micro-volume instrument of FIG. 1;

FIG. 9 is a bottom plan view of the ultra-small, micro-volume instrument portion of FIG. 8;

FIG. 10 is a top plan view of the ultra-small, micro-volume instrument portion of FIG. 8 in a working environment;

FIG. 11 is a rear elevation view of the ultra-small, micro-volume instrument portion of FIG. 8; and,

FIG. 12 is a top, front, right isometric perspective view of the ultra-small, micro-volume instrument portion of FIG. 8 in a working environment.

The broken lines in the drawing views are included for the purpose of illustrating portions of the ultra-small, micro-volume instrument unit assembly that form no part of the claimed design.

1 Claim, 8 Drawing Sheets
